EXTENSION LADDER AND LOCK THEREFOR

Roy O. Balogh and Eugene G. Humpal, Cleveland, Ohio, assignors, by mesne assignments, to McCabe-Powers Auto Body Co., St. Louis, Mo., a corporation of Missouri

Application November 8, 1949, Serial No. 126,179

6 Claims. (Cl. 228—18)

1

This invention relates to an extension ladder carried by a vehicle and adapted to lie in approximately horizontal position during travel of the vehicle and be raised at an angle for use. With an extension ladder so carried there is a tendency of the extension portion to shoot forward on the supporting portion by momentum whenever the vehicle suddenly stops. Our invention is directed to automatic means for locking the extension and preventing such displacement when the ladder is horizontal while allowing free movement of the extension portion when the ladder is tipped up for use.

Means by which we accomplish this automatic locking of the extension portion of the ladder is illustrated in a preferred form in the drawings hereof and hereinafter more fully described and its essential novel features are summarized in the claims.

In the drawings, Fig. 1 is a side elevation, partly broken away, of a highway truck equipped with an extension ladder pivotally mounted on the pedestal carried by the truck; Fig. 2 is a plan of a portion of the extension ladder over the pedestal in the region indicated by the line 2—2 on Fig. 1; Fig. 3 is a rear elevation of the same portion in the region indicated by the line 3—3 on Fig. 1; Fig. 4 is a side elevation on a larger scale of the pedestal and adjacent portion of the ladder disclosing our latch in operative position to lock the extension ladder; Fig. 5 is a side elevation partly broken away of the same parts with the ladder tipped upwardly; Fig. 6 is a view of the pedestal and ladder with the ladder raised to the maximum.

As shown in Fig. 1, A indicates any suitable vehicle, for instance, a highway truck. 10 designates a vertical post comprising the stationary portion of the ladder-supporting pedestal, mounted on the truck, this post having a spreading base 11 by which it is rigidly held in the upright position. Embracing the post 10 so as to be rotatively mounted thereon is a vertical sleeve 12 which has a rectangular head 13. Two side rails 20 of the main ladder extend onto opposite sides of this head and are pivotally secured to it by a transverse shaft 15. The rungs 21 of the main ladder extend from one of the rails 20 to the other in the usual manner.

The extension ladder has side rails 30 which may rest on the rungs 21 of the main ladder and carry their own rungs 31. Suitable means, not shown, may be provided to slidably hold the extension ladder on the main ladder, as well as means to propel the extension ladder along the

main ladder to extend the same as desired. A hand wheel 17 rotatably carried by the sleeve head 13 may operate suitable mechanism (not shown) to swing the ladders laterally as a unit.

5 To tip the ladders as a unit on the pivot 15, we provide a piston and cylinder construction adapted to be actuated by fluid pressure. We have shown a cylinder 40 pivoted at 41 to a bracket 42 on the sleeve 12 and a piston having axially extending rod 45 connected to the main ladder by rigid brace bars 46 and 47. Suitable fluid pressure acting on the piston at the lower end of the rod 45 serves to tip the combined ladders upwardly into various positions, as indicated in Figs. 5 and 6.

To enable ready access to the ladders there is provided a step ladder 50 shown as pivoted by a cross rod 51 to a rearwardly extending portion of the main ladder. The lower portion of this

20 step ladder rests slidably against a bracket 52 carried by the sleeve 12. As the ladders 20 and 30 are tipped up, the step ladder 50 slides downwardly across the supporting bracket 52, as indicated by the broken lines in Fig. 1 and as shown 25 in Fig. 6.

20 To lock the extension ladder 30 in place on the main ladder 20 when the ladders are horizontal, we provide a lever latch 60 pivoted on the pivot rod 51 and extending forwardly beneath the endmost rung 31 of the extension ladder in its unextended position. This latch has an upwardly extending jaw at its free end adapted to hook around such rearmost rung 31. A pin 61 on the step ladder beneath the latch limits its downward movement and a tension spring 62 tends to 35 maintain the latch in engagement with the stop pin as shown in Figs. 4 and 5.

It will be seen from Fig. 4 that when the ladders are horizontal the latch is definitely retained in a position hooking around the rearmost rung 40 of the extension ladder and effectively locking it to the main ladder. When, however, the ladders are swung upwardly, by the operation of the piston and cylinder mechanism, as indicated for instance in Fig. 5, such movement frees the extension ladder from the latch, so that the extension ladder may be elevated along the main ladder.

When the ladders are raised the maximum amount, as shown in Fig. 6, this may bring the latch against the head 13 of the carrying sleeve. If so, the latch simply swings upwardly on its pivot, stretching the spring 62, as shown in this figure.

55 It will be seen from the description given that

we have provided a very simple automatic lock for preventing shifting of an extension ladder during its transportation. As soon as the ladder is tipped for use, the lock is automatically released from the extension so that the latter may be shoved lengthwise of the supporting ladder in the usual manner. When the operator is through using the ladder in its extended position the ordinary operation is to lower the extension to its initial position and thereafter tip the combined ladder downwardly into horizontal position. At the conclusion of such tipping movement the latch again becomes effective to automatically lock the extension ladder, so that it cannot be jarred or forced by momentum or gravity out of position on the main ladder.

We claim:

1. The combination of a supported standard, a main ladder pivoted thereto on a horizontal pivot, an extension ladder slideable lengthwise on the main ladder for disposition optionally in extended and retracted positions relative to the main ladder, a latch carried by the main ladder and adapted to engage the extension ladder or be free therefrom, a depending step ladder pivotally carried by the main ladder, and a stop on the step ladder adapted to hold the latch in engagement with the extension when the extension ladder and main ladder are substantially horizontal and the extension ladder is in retracted position.

2. The combination of a substantially vertical support, a main ladder pivoted thereto for optional movement from a substantially horizontal position to an angularly disposed upright position, said main ladder when in horizontal position extending forwardly from the support and having a terminal portion extending rearwardly from the support, an extension ladder slideable lengthwise on the main ladder for disposition optionally in extended and retracted positions relative to the main ladder, a step ladder pivoted to the terminal portion of the main ladder and extending downwardly therefrom at the rear of the support, whereby the step ladder is lowered vertically when the main ladder is pivoted upwardly on the support, a latch pivotally mounted on and extending forwardly from the pivot of the step ladder, said latch having a detent-element positioned for engagement with the extension ladder when the extension ladder and main ladder are substantially horizontal and the extension ladder is in retracted position to hold the extension ladder against unauthorized forward movement, and a stop on the stepladder for engaging and holding the latch in such position when the main and extension ladders are horizontal.

3. The combination of a substantially vertical support, a main ladder pivoted thereto for optional movement from a substantially horizontal position to an angularly disposed upright position, said main ladder when in horizontal position extending forwardly from the support and having a terminal portion extending rearwardly from the support, an extension ladder slideable lengthwise on the main ladder for disposition optionally in extended and retracted positions relative to the main ladder, a downwardly extending step ladder pivoted to the terminal portion of the main ladder and extending downwardly therefrom at the rear of the support, a latch carried by and extending forwardly from the step ladder, said latch having a detent-element positioned for engagement with the extension ladder when the extension ladder and main ladder are

substantially horizontal and the extension ladder is in retracted position to hold the extension ladder against unauthorized forward movement when the main and extension ladders are horizontal, and means for holding the latch and stepladder together for simultaneously swinging movement downwardly and away from the main ladder as the latter is pivoted upwardly on the support thereby disengaging the detent-element from the extension ladder to permit said extension ladder to be extended upwardly and forwardly in relation to the main ladder.

4. The combination of a substantially vertical support, a main ladder pivoted to the support for optional movement from a substantially horizontal position to an angularly disposed upright position, said main ladder when in horizontal position extending forwardly from the support and having a terminal portion extending rearwardly from the support, an extension ladder mounted on the main ladder and slideable lengthwise of the main ladder for optional disposition in extended and retracted positions relative to the main ladder and having a plurality of spaced parallel rungs, a depending step ladder pivotally mounted on the terminal portion of the main ladder, bracket means extending rearwardly from the support and slidably engaging the step ladder for holding the step ladder in depending position as it shifts downwardly responsive to upward tilting movement of the forward end of the main ladder, a latch carried by and extending forwardly from the step ladder and having an upwardly extending hook adapted to engage one of the rungs of the extension ladder when the extension and main ladders are horizontal and the extension ladder is in retracted position, a stop mounted on the step ladder and positioned for normally engaging the underside of the latch, a spring normally biasing the latch downwardly against the stop, the stop being positioned to hold the latch in said rung-engaging position whereby the latch hook is caused to release the extension ladder responsive to lowering of the step ladder and the stop when the main and extension ladders are tipped, said spring furthermore allowing the latch to swing relatively upwardly if it comes into engagement with the support after being released from the extension ladder.

5. The combination of a support, a main ladder pivoted thereto a comparatively short distance in front of its rear end, an extension ladder slidably mounted on the main ladder for disposition optionally in extended and retracted positions relative to the main ladder, a latch pivoted to the main ladder at the rear of the pivot of the main ladder and engaging the extension ladder to lock the ladders together in one direction when they are substantially horizontal and the extension ladder is in retracted position, and means for retaining the latch extending in an approximately fixed direction as its pivot is lowered by the upward tipping of the ladders, whereby such an upward tipping frees the extension ladder from the latch.

6. The combination of a support, a main ladder pivoted thereto a relatively short distance in front of its rear end, an extension ladder slidably mounted on the main ladder for disposition optionally in extended and retracted positions relative to the main ladder, a latch pivotally carried by the main ladder and extending forwardly and having an upwardly extending jaw adapted to engage the extension ladder when the ladders are substantially horizontal and the extension

ladder is in retracted position, a depending member pivotally carried by the main ladder, bracket means extending from the support and slidably engaging the depending member for guiding the latter to move in an approximately constant up-and-down direction as the main and extension ladders are tipped, a stop on said depending member, and a spring normally maintaining the latch in engagement with the stop to hold the latch extended in a substantially constant direction as its pivot is lowered by the upward tipping of the ladders.
